FRANK S. INGOLDSBY AND JOSEPH R. BOWLING, OF ST. LOUIS, MISSOURI,
ASSIGNORS TO THE INGOLDSBY AUTOMATIC CAR COMPANY, OF ST. LOUIS,
MISSOURI, A CORPORATION OF WEST VIRGINIA.

BOLSTER FOR RAILWAY-CARS.

SPECIFICATION forming part of Letters Patent No. 694,385, dated March 4, 1902.

Application filed July 13, 1901. Serial No. 68,128. (No model.)

To all whom it may concern:

Be it known that we, FRANK S. INGOLDSBY and JOSEPH R. BOWLING, citizens of the United States, residing at St. Louis, in the 5 State of Missouri, have invented a certain new and useful Improvement in Bolsters for Railway-Cars, of which the following is a full, clear, and exact description, reference being had to the accompanying drawings.

10 The object of this invention is to provide a steel bolster for railway-cars which while being cheap to construct shall be very light, strong, and rigid in operation.

Our bolster is particularly designed for use 15 with steel cars and may be conveniently employed in steel dump-cars.

The invention may be best summarized as 20 consisting of the combinations of elements hereinafter described, and definitely set out in the claims.

The drawings clearly illustrate a body-bolster having our invention, Figure 1 being a side elevation of a little more than half thereof; Fig. 2, a bottom plan of the same, and Fig. 25 3 a top plan thereof. Fig. 4 is a vertical central section through the bolster. Fig. 5 is a vertical section on the line 5 5 of Fig. 1 looking toward the center of the bolster. Fig. 6 is a similar section on the line 6 6 of Fig. 1. 30 Fig. 7 is a top view of the center bearing. Fig. 8 is a horizontal section on the line 8 8 of Fig. 1.

The same letters of reference designate the same part in each figure.

35 As shown in the drawing, our bolster includes a central box-like casting or frame A, a compression member B, extending diagonally downward across the lower end of the frame, and a tension member C, extending 40 diagonally upward across the upper end of the frame, the extreme ends of the members C and B being secured together. The central frame A is of the form shown, having a horizontal top plate a and a horizontal bottom plate a' and vertical side plates a² a². These parts are all strengthened by a pair of webs a³. The compression member B lies in contact with the under side of the plate a' and is riveted thereto by the rivets d. This 45 plate a' has its edges flanged downward, as at a⁴, making, in effect, a shallow inverted channel at the base of the frame, in which takes the compression member B. The tension member C is a flat plate lying in contact with the upper side of the plate a and riveted thereto. The extreme ends c' of the tension member are turned downward across the ends of the channel member B. Within the channel member, near its end, is the reinforcing-casting E, riveted to the flanges of the channel 55 member by the various rivets d². This casting E is in the form of an inverted box, as shown, having a top plate and side and end flanges, the outer end flange e contacting the downturned end c' of the tension member and 60 the two being riveted together by the rivets d³. A filling-block F lies between the compression and tension members at their ends, and the parts here are all bound in place by the rivets d⁴ d⁵, which pass through the tension member, the filling-block, the compression member, and the reinforcing-casting E. The arrangement of these coöperating parts at the end of the bolster, as above described, 65 has many advantages. It materially stiffens 70 the end of the bolster and greatly aids in preventing the same from bending downward, due to the weight of the superincumbent side of the car. It obviates the necessity of bending the channel member B, which would be 75 difficult. It distributes the thrust to the web and both flanges of this channel member. It provides convenient surfaces for the reception of various rivets desired. It lessens the liability of the tearing apart of the end of the 80 bolster, as the filling-block F allows the rivets d⁴ to take a shearing strain only instead of having both a shearing and tension strain as they would if this filling-block were omitted. The result of these various features is that a 85 particularly strong, light, and efficient construction is provided.

The drawing shows a channel-shaped side sill G and an inclined side strut H, riveted together and both resting on the tension 90 member C and held in place by the rivets d⁵, passing through flanges of these members in addition to the tension member, the filling-

block, the compression member, and its reinforcing-block, as shown. The arrangement of the side sill and the side strut, however, is shown simply as illustrative and is not a portion of this invention.

Between the filling-block F and the center casting A we brace the bolster by a suitable intermediate vertical strut. As shown, this strut consists of the horizontal beam J, passing diagonally through the bolster, the filling-block K above it, and the filling-block L below it. Rivets d^6 pass through the tension member C, the filling-block K, and the flange of the beam J, which is preferably an I-beam, binding these parts together, while below rivets d^7 secure the I-beam to the filling-block L, and rivets d^8 secure the latter filling-block to the compression member B. These latter rivets also hold in place the side bearing M, which is a casting seating within the channel B. The block L is preferably cored, as indicated, having top and bottom and side walls and cross-webs. The bolster is further strengthened by the diagonal strut P, which is shown as an angle-bar, riveted at d^9 to the channel member B at the side of the central frame and riveted to the tension member C and the filling-block K by a connection-plate p, which seats within the filling-block and is pierced by some of the rivets d^6 . The bolster is still further strengthened by a pair of tension-rods Q, secured at one end to the central casting A by the bolts R, which pass through that casting and have on their ends nuts r, which clamp eyes in the ends of the bars Q, which surround the bolts. The other ends of these bars Q take diagonally through the filling-blocks L, through the compression members B beneath the same, and through the side bearings M and are adjusted by nuts q, bearing against those side bearings. The simple tightening of these latter nuts would thus true up the bolster, if any derangement of the car should cause the side bearings to sag.

The center bearing, which seats in the channel member B, is a channel-shaped block S, having the top plate and side flanges s' and at its center the cylindrical boss s². The boss has a horizontal lower face s⁴ and an inner tubular walls s³ and four internal cross-webs s⁵, which come directly beneath the webs a³ of the central frame, whereby the strains due to the weight of the load are transmitted directly through those webs. The peripheral face s² and the horizontal face s⁴ of the boss form the rubbing-surface for the corresponding member in the truck-bolster. A king-pin T occupies the tube s³ and projects up into the casting A between the webs a³ thereof and is there locked by a key t. The drawing shows vertical plates U lying against the outer surface of the sides a² of the center casting and riveted thereto by the rivets d¹². These plates extend toward the end of the car, forming the draft-beam. They are shown also as extending

in the other direction and are adapted to be connected with a center sill or truss, which is used especially in dumping-cars. Fig. 70 4 shows this construction. The plate U at the right is braced by the angle-strips u and forms part of the draft-beam. At the left the lower edge of the plate is cut off diagonally and braced by the angle-strip u', 75 while at its upper edge the plate is also secured to the side of an upper cord of the center truss. This upper cord, as shown, consists of the inverted channel-beam V, surmounted by the inverted-T beam W, the plate U being riveted to the channel-beam. As shown, these beams W and V project into the bolster beneath the tension member C (the flange of the T-beam being removed) and are there supported by the bracket Y, which is held to the casting by some of the same rivets d² which hold the side plates E. The drawing, Figs. 4 and 5, also show an inclined tension member Z, which is the end of the lower chord of the trussed center. This tension member has its upper end horizontal, extending across the bracket Y, and being gibbed up across the end of the channel V and the T-beam, as shown at z.

The above arrangement of trussed center beam and the plates U is not a part of the present invention, but is illustrated herein to show how these parts may be connected to the bolster.

Having described our invention, we claim— 100

1. In a bolster, in combination, a central frame, a channel-shaped compression member extending across the frame in each direction, a tension member extending across the frame and secured to it, the ends of said tension member and channel member being secured together, and a center bearing within the channel member where it crosses the frame, substantially as described.

2. In a bolster, in combination, a central frame, a channel-shaped compression member extending across one end of the frame in each direction, a tension member extending in each direction from the other end of the frame, the ends of said tension and compression members being secured together, a center bearing in the form of a channel-shaped block carrying a boss, and rivets binding the center bearing, the compression member and the central frame together, substantially as described.

3. In a bolster, in combination, a central frame, a tension member extending from the frame, a compression member secured to said central frame and extending therefrom, a reinforce riveted to the compression member near its free end, the end of said tension member being turned across the end of the compression member and riveted to such reinforce, substantially as described.

4. In a bolster, in combination, a central frame, a tension member extending from the frame, a compression member in the form of a channel-beam secured to the central frame

and extending therefrom, a reinforce within the channel member near its free end and riveted to the side flanges thereof the end of said tension member being turned across the end of the compression member and riveted to such reinforce.

5. In a bolster, in combination, a central frame, a tension member extending from the frame, a compression member secured to the frame and extending therefrom said tension and compression members approaching each other at their free ends, a filling-block between said free ends, a reinforce adjacent to the compression member, the end of the tension member being turned across such reinforce, and two sets of rivets one binding the reinforce and tension member together and the other binding the reinforce, the compression member, the filling-block, and the tension member together, substantially as described.

6. In a bolster, in combination, a central frame, a compression member in the form of a channel-beam secured thereto and extending laterally therefrom, a tension member in the form of a flat strap secured to the casting and extending therefrom, said tension and compression members approaching each other as they recede from the central frame, a wedge-shaped filling-block between said tension and compression members near the free ends thereof, and rivets extending through such tension member the filling-block and the compression member, substantially as described.

7. In a bolster, in combination, a central frame, a compression member in the form of a channel-beam secured thereto and extending laterally therefrom, a tension member in the form of a flat strap secured to the casting and extending therefrom, said tension and compression members approaching each other as they recede from the central frame, a wedge-shaped filling-block between said tension member and compression member near the free ends thereof, a flanged reinforcing member within the channel-beam near its free end, rivets extending through the tension member, the wedge-shaped filling-block, channel member and the reinforcing member and binding said parts rigidly together, and other rivets binding the flanges of the channel member and the flanges of the reinforcing-block, substantially as described.

8. In a bolster, in combination, a central frame, a tension member extending across the frame and secured to it, a compression member in the form of a channel-beam secured to said central frame and extending therefrom, a flanged reinforce within the channel member near its free end and riveted to the side flanges thereof, the end of said tension member being turned across the end of the channel member and riveted to such reinforce, and a filling-block between the tension member and compression member, and rivets extending through the tension

member, the filling-block, the compression member and such reinforce, substantially as described.

9. In a bolster, in combination, a central frame, tension and compression members extending diagonally therefrom and having their free ends secured together, an intermediate strut between such tension and compression members and secured to each of them, and a diagonal strut secured to the tension member adjacent to such intermediate strut and to the bolster adjacent to the central frame, substantially as described.

10. In a bolster, in combination, a central frame, tension and compression members extending diagonally therefrom and having their free ends secured together, an intermediate vertical strut between such tension and compression members and secured to each of them, a diagonal strut seating at one end between such intermediate strut and the tension member and there secured and at the other end riveted to the compression member, substantially as described.

11. In a bolster, in combination, a central frame, tension and compression members secured to the same and extending diagonally and having their free ends secured together, and a diagonal tension-rod secured to the central frame and extending through the compression member, and means for adjusting said rod, substantially as described.

12. In a bolster, in combination, a central frame, diagonal tension and compression members secured thereto and having their free ends secured together, a side bearing carried by said compression member, a diagonal tension-rod secured to said central frame and extending through said compression member and through said side bearing, and a nut screwing onto said tension-rod and bearing against said side bearing, substantially as described.

13. In a bolster, in combination, a central frame, diagonal tension and compression members secured thereto and having their free ends secured together, a side bearing carried by said compression member, a pair of diagonal tension-rods secured to said central frame and extending through said compression member and through said side bearing, nuts screwing onto said tension-rods and bearing against said side bearing, a rigid strut between the tension and compression members in the line of the side bearing, and a diagonal brace leading from the tension member to the bolster near the lower end of the central frame and lying between said diagonal tension-rods, substantially as described.

14. In a bolster, in combination, a central frame, a compression member extending diagonally in each direction from opposite sides thereof, a tension member extending across the frame and having its opposite ends secured to the ends of the compression member, diagonal tension-rods leading from opposite

sides of the central frame to said compression member and secured at their outer ends thereto, and a bolt passing through said central frame and securing the inner ends of said two tension-rods, substantially as described.

15. In a bolster, in combination, a central frame, a channel-shaped compression member extending across one end thereof and leading diagonally therefrom in each direction, a tension member extending across the other end of the frame and leading diagonally toward the compression member the free ends of said tension and compression members being secured together, a pair of side bearings on opposite sides of said central frame seating in said channel-shaped member, diagonal tension-rods leading from opposite sides of the central frame to said compression member and passing through the compression member 20 and through the side bearings, nuts screwing onto the ends of said tension-rods and bearing against said side bearings, and a bolt passing through said central frame and securing the inner ends of said tension-rods, substantially as described.

25. In a bolster, in combination, a central frame having a pair of webs across it, a channel-shaped compression member extending

across the frame in each direction, a tension member extending across the frame and secured to it, the ends of said tension member and channel member being secured together, and a center bearing seating in the channel member where it crosses the frame, said center bearing being a cored structure with vertical webs directly beneath the cross-webs of the frame, substantially as described.

30. 17. In a bolster, in combination, a central frame, a channel-shaped compression member extending across the frame in each direction, a tension member extending across the frame and secured to it, the ends of said tension member and channel member being secured together, and a center bearing within the channel member where it crosses the frame, said central frame having a pair of webs across it, and a king-pin extending through the center bearing into the space between said webs, substantially as described.

35. In testimony whereof we hereunto affix our signatures in the presence of two witnesses.

FRANK S. INGOLDSBY.
JOSEPH R. BOWLING.
